CLAIM

The ornamental design for a foot-deck based vehicle, as shown and described.

DESCRIPTION

FIG. 1 is a perspective view from above, to the front and to the left side of a first embodiment of a new design for a foot-deck based vehicle;

FIG. 2 is a top plan view thereof;

FIG. 3 is a bottom plan view thereof

FIG. 4 is a right side elevation view thereof;

FIG. 5 is a left side elevation view thereof;

FIG. 6 is a front elevation view thereof;

FIG. 7 is a rear elevation view thereof;

FIG. 8 is a perspective view from above, to the front and to the left side of a second embodiment of a new design for a foot-deck based vehicle;

FIG. 9 is a top plan view thereof;

FIG. 10 is a bottom plan view thereof

FIG. 11 is a right side elevation view thereof;

FIG. 12 is a left side elevation view thereof;

FIG. 13 is a front elevation view thereof; and,

FIG. 14 is a rear elevation view thereof.

The broken lines shown in the drawings are for illustration only and form no part of the claimed design.
